UNITED STATES PATENT OFFICE.

EDWIN R. WHITTIER, OF BEVERLY, MASSACHUSETTS.

GAME APPARATUS.

1,166,164.

Specification of Letters Patent. Patented Dec. 28, 1915.

Application filed July 31, 1914, Serial No. 854,224. Renewed August 25, 1915. Serial No. 47,323.

To all whom it may concern:

Be it known that I, EDWIN R. WHITTIER, of Beverly, Massachusetts, have invented certain Improvements in Game Apparatus, 5 of which the following description, in connection with the accompanying drawings, is a specification, like characters on the drawings designating like parts.

This invention relates to games and has 10 for its object the provision of a return ball game which may be played by one or preferably more contestants, the principal feature of the game being the attempt to throw the ball into a basket in such a manner that 15 the ball will escape through a suitable exit in the bottom of the basket and thence be led to a point near the player himself, suitable conduits being provided leading from corresponding exits in the basket to each 20 of the players, and the feature of competition being introduced by penalizing the player, whose ball, when thrown, goes to another player through the exit and conduit leading thereto, instead of returning to the 25 player throwing the ball.

Among other important objects of my invention is the provision of apparatus which can be cheaply constructed, easily installed upon the ground outside the house or upon 30 the floor within the house, and which apparatus includes the central basket with its apertured bottom and means to support this basket at a relatively high level while the conduits lead outwardly and downwardly 35 therefrom in radial directions to suitable posts or other supports which may have pockets for the reception of a supply of balls, for each of the players, who stand by their respective posts at a suitable distance radially from the basket to make the 40 accuracy of their throw difficult but not impossible.

The various features of my invention will be illustrated and described fully in the 45 accompanying drawings and specification and pointed out in the claims.

In the drawings, Figure 1 is a view in perspective of an outdoor game, constructed in accordance with my invention; Fig. 2 50 is a plan view of the central basket or receptacle on a larger scale; Fig. 3 illustrates a modified form of support for the game post or posts; Fig. 4 illustrates a modified form of the central receptacle, in vertical section, 55 also upon a larger scale taken on the line

$\alpha^4-\alpha^4$, Fig. 5; Fig. 5 is a plan view thereof, similar to Fig. 2.

In the embodiment of my invention selected for illustration and description to enable ready and complete understanding of 60 my improvements, the part designated by the reference numeral 1 is the central receptacle of my improved game, into which it is the object of the game to throw a ball or balls in such a manner that the ball will 65 enter the aperture 2 (see Fig. 2) from which the ball will pass to a conduit 3 leading toward the player himself, and having a support 4 at its outer end.

The central receptacle may be of any suitable shape or material, and in this instance, is shown as being a basket, with an ordinary bottom 5 with several apertures 2 formed therein. The basket is screwed or otherwise secured at the top of the support 6 which 70 may be of any suitable construction, and, in the instance illustrated, takes the form of a pointed stake or post driven into the ground. To these stakes are secured also one set of the ends of each of the conduits 75 3, the latter being of any suitable construction, and taking the form, in the instance illustrated, of tapes or bands secured at each end in such a fashion as to present a trough to receive and direct the ball toward the 80 outer ends, at which region they may be supported by the posts 4, driven into the ground, or provided respectively with bases or feet 8, which latter are shown best in Fig. 3 and will be found of greatest utility 85 90 when the game is to be played in the house or in some other place where sharp pointed stakes cannot be used to advantage.

I prefer to so attach the conduits 3 to their supporting stakes that the balls, upon 95 their return respectively to the stakes of the individual player, will be arrested in a conspicuous position, for the purposes of tally, as shown in Fig. 1, and in order that these need not be disturbed, I prefer to provide 100 also, a suitable storage receptacle for a supply of balls to be used by the players, one pocket or receptacle 9 for each stake. These receptacles may be of any convenient structure and are shown as reticules supported by 105 hoops 10 fastened each to one of the stakes 4.

In operation, the players take their position each near one of the stakes 4 and the players in turn withdraw balls from the receptacles 9 and throw them into the central 110

receptacle 1. If a ball rolls into an aperture leading to the conduit of the player tossing the ball, the play counts for that player, but if the ball passes through a different aperture and is directed through one of the other conduits toward the stake of an opponent, the tally is for that opponent.

In order to vary somewhat the chances of getting the ball to pass through the desired exit, if desired a suitable obstacle may be placed in the receptacle to baffle the ball and as one convenient form of such a baffle, I have shown at 15 an extension of a post 14, carrying a bell 17, this being illustrated best 15 in Fig. 4 and Fig. 5. In this modification I have shown a series of separators 12, entering grooves 13 in the post 14 and also in grooves 18 in the bottom 5, and serving both to divide the basket into compartments, corresponding with the holes 2, and to maintain in distended position the flexible walls 16 of the basket, when the latter is made of a woven or netted fabric, as it may be, conveniently, formed at its mouth upon a wire 25 hoop 19.

With such a structure, the withdrawal of separators 12 permits the collapse of the walls 16 with hoop 19 against the bottom 5, and upon withdrawal of the post 14, the several parts can be packed compactly in a suitable case, such as the box for a croquet set.

Having illustrated and described my invention thus fully and suitable means for carrying the same into effect, it is to be understood that I do not limit myself to the specific structure and materials selected for illustration and description by way of example, nor do I limit myself in general otherwise than as set forth in the claims read 30 in connection with my specification.

What I claim as new and desire to secure by Letters Patent of the United States is:—

1. A game comprising a central collapsible receptacle and laterally extensible 45 flexible conduits; said receptacle being open to receive counters tossed thereinto by a player or players stationed each near the

outer portions of one of said conduits when extended, and having openings to pass said counters into said conduits; and means to support said central receptacle and the outer portions of said conduits respectively in such a manner that said counters will roll from the central receptacle toward the outer portions of said conduits.

2. A game comprising a central receptacle opening upwardly to receive counters tossed thereinto, and a post therefor; a series of flexible bands extensible radially to form curved conduits leading downwardly and outwardly from said central receptacle, and having a series of supports, one for and to hold the extended end of each of said conduits, said receptacle having openings leading to said conduits respectively.

3. A game comprising a central receptacle and a post therefor; a series of laterally extended bands curved to form conduits leading downwardly and outwardly from said central receptacle, and having a series of supports, one for and to hold the extended end of each of said conduits; and a storage receptacle for counters, one for and carried by each of said outer supports; said central receptacle having openings leading to said conduits respectively, and said conduits being connected to said outer supports in such a manner that the counters traversing said conduits respectively will be arrested adjacent to the outer support of each conduit.

4. A game comprising a central receptacle having openings in its lower portion and conduits leading therefrom toward the point of play of the individual players; and a baffle device within said central receptacle to engage a counter tossed thereinto.

Signed at Beverly, in the county of Essex and State of Massachusetts this 13th day of July, 1914.

EDWIN R. WHITTIER.
